UNITED STATES PATENT OFFICE.

CHARLES E. DAVIS AND GEORGE ENGEL, OF LIBERAL, KANSAS, ASSIGNEES, BY DIRECT AND MESNE ASSIGNMENTS, TO E. P. FOX, OF LIBERAL, KANSAS.

FIXTURE FOR ROLLING-AWNING FRAMES.

Application filed September 24, 1926. Serial No. 137,502.

This invention relates to rolling awnings, more particularly to a fixture for the frame of the awning body, and has for its object to provide, in a manner as hereinafter set forth, a fixture for the frame of a rolling awning for releasably securing the awning in any desired angular position to exclude sun or heat and for ventilating purposes and further whereby the awning can be adjusted to and held in vertical position to perform the function of a vertically disposed shade.

Further objects of the invention are to provide, in a manner as hereinafter set forth, a fixture for a rolling awning frame, which is simple in its construction and arrangement, strong, durable, compact, thoroughly efficient in its use, conveniently adjusted, readily installed with respect to the door or window, and comparatively inexpensive to set up.

With the foregoing and other objects in view, the invention consists of the novel construction, combination and arrangement of parts as hereinafter more specifically described and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:

Figure 1 is a fragmentary view, in side elevation, of an automobile body, showing the adaptation with the door thereof of a rolling awning having installed therewith a fixture in accordance with this invention.

Figure 2 is a vertical sectional view of the door of an automobile body showing the adaptation therewith of an awning having installed therewith a fixture in accordance with this invention.

Figure 3 is a perspective view of the combined holding and extension frame for the flexible body portion of the awning.

Figure 4 is a fragmentary view, in elevation, of a modified form.

Figure 5 is a section on line 5—5 Figure 4.

Figure 6 is a view similar to Figure 4, of another modified form.

Figure 7 is a section on line 7—7 Figure 6.

Figure 8 is a detail illustrating a locking member looking towards the inner face thereof employed in connection with the forms shown in Figures 4 and 6.

Figure 9 is a detail illustrating a coupling member, looking towards the outer face thereof, employed in connection with the forms shown in Figures 4 and 6.

The awning body which is referred to by the reference character 1 is constructed of any suitable flexible material, of the desired length and width, such as rubberized fabric, oil treated duck, canvas, leather fabric, silk, linen or any other suitable material. The awning body 1 is associated with a spring controlled roller referred to generally by the reference character 2 and which normally maintains the awning body 1 in a rolled up position. The awning body 1 is withdrawn from the roller 2 against the action of the controlling spring for the latter, and when the awning body 1 is released it automatically winds up on the roller 2 due to the action of the controlling spring of the latter.

Connected to the lower end of the awning body 1, is a combined holding and extension frame therefor and which is referred to generally by the reference character 3. The frame 3 comprises a front bar 4 and a pair of side arms 5, 6 and each of the latter is formed with a lengthwise extending slot 7. The arms 5 and 6 are formed from a round or flat bar of suitable material, preferably metal, and each of said arms terminates at its forward end in a rearwardly directed angularly disposed portion 6' of the bar 4. The bar 4 is cylindrical in cross section and its diameter is materially less than the width of either the arms 5, 6. The combined holding and extension frame is of yoke-shaped contour. The awning body 1 at its outer end is lapped around the bar 4, and secured together, whereby the outer end of said awning body 1 is fixedly secured to the bar 4 and said awning body 1 is bodily carried

with the frame 3 or the latter is bodily carried with the awning body 1. The overlapping portion of the awning body 1, which surrounds the bar 4, is indicated at 8 and 5 it is stitched in position as indicated at 9.

The roller 2 is of the general type of spring curtain rollers and is supported in the brackets 10 and 11.

The arms 5, 6 are slidably mounted on a 10 pair of supports 12, and each of which consists of a threaded bolt having the threaded portion thereof provided with a wing nut 13, for the purpose of binding against an arm 5 or 6 to fixedly secure the frame 3 in 15 its adjusted position.

The body of an automobile of the closed type is indicated at 14 and one of its doors at 15. The fixtures 10 and 11 are secured to the sides 16 of the door frame and extend 20 rearwardly therefrom. The roller 2 is supported from the door 15 at the rear thereof. The supports 12 extend through the sides of the door frame, are countersunk therein and project inwardly from said sides as shown 25 in Figure 1. The awning body 1 and frame 3 are positioned within the door frame and when the awning is in closed position it is arranged rearwardly with respect to the vertically movable transparent panel 17 of the 30 door.

The setting up of the frame 3 in the manner as stated, permits of the latter to be shifted forwardly and rearwardly with respect to the door 15 and after being shifted 25 will be locked or rather secured in such position. The frame 3 can be set at any angular position with respect to the door 15 and when set automatically unwinds the awning body 1 when the roller 2 is released. The 10 frame 3 can also be set to a vertical position with respect to the door 15 as shown in dotted lines in Figure 2 whereby the awning body 1 will be vertically disposed and perform the function of a shade.

15 Figures 4 and 6 illustrate the combined holding and extension frame of the adjustable type for different widths of awning bodies. The frame in Figure 5 is indicated generally at 22 and in Figure 7 generally at 23. Each frame comprises a pair of oppositely disposed L-shaped bars and a tubular member mounted on the bars. Each bar consists of an outer and a side arm disposed at right angles with respect to each other. 20 The tubular member is mounted upon the outer arms of the pair of bars. The outer arm of each bar extends inwardly from the outer end of a side arm.

In Figure 4, the bars are indicated generally at 24, 25, the outer arms of the bars at 26, 27 and the side arms of the bars at 28, 29. The bars can be of any suitable cross section, and as shown by way of example, are circular. The inner end of each arm 28, 29 is reduced as at 30 and which has secured there-

with a stop member 31 of any suitable shape, and as shown of globular contour. The tubular member is indicated at 32 and into which slidably extends the arms 26, 27. The member 32 is of a length to extend to the 70 points of joinder between the arms of the bars 24, 25. The outer end of the awning body 1 is adapted to be secured to the member 32. The side arms 28, 29 are adjustably mounted in a pair of revoluble locking members 33 and each of which consists of a polygonal shaped disk like body 34, formed with an axial opening 35, a horizontally disposed opening 36 to one side of the latter, an opening 37 at one side of the opening 35 and 75 which communicates at its inner end with the opening 36 and at its outer end opens at one side of the disk. The wall of the opening 37 is threaded. The inner face of the disk 34 is toothed or serrated as indicated at 80 38. The openings 36 of the members 33 correspond in contour to the shape of the arms 28, 29 and these latter are slidably mounted in said openings whereby said arms can be adjusted forwardly and rearwardly with respect to the disks, and further so that on the 85 revolving movement of the disks the bars 24, 25 and member 32 will be carried therewith. The outward shifting of the bars 24, 25 is arrested by the stop members 31 abutting 90 the disks 34. The arms 28, 29 are retained in adjusted position by the set screws 39 which threadably engage with the walls of the openings 37 and bind against the said arms see Figure 5.

The locking members 33, are revolvably mounted upon a pair of bolts 40, each carried by a coupling member 41, secured by the hold fast devices 42 to one of the sides 105 16 of the door or window frame. The bolts 40 have their heads 43 countersunk in the inner face of the members 41 and each of these latter on the outer face thereof is formed with an enlargement 44 which corresponds 110 in contour to the shape of a locking member 33. The enlargement 44 is serrated or toothed as at 45 to co-act with the toothed inner face of the member 33 to prevent the latter from shifting when it is clamped in position by a clamping nut 46, of the wing type, which is mounted on the bolt 40 adjacent the outer face of the member 33.

The form shown in Figure 6, is the same as that shown in Figure 4, with this exception that the side arms of the holding and extension frame and the locking members are constructed differently. In Figure 6 the tubular member is indicated at 47, the L-shaped bars at 48, 49, the outer arms of the bars at 50, 51, the side arms of the bars at 52, 53 and the locking members at 54, 55. Each locking member is formed with a wide opening 56 for the passage of a side arm, and such opening is intersected by the opening 57 for the pivot bolt 58. Each locking 120 125 130

member is also formed with an opening 59 for the set screw 60. Each side arm is provided with a lengthwise extending slot 61 through which extends the pivot bolt 58.

- 5 The inner end wall 62, of the slot 60 arrests the outward movement of a side arm. Otherwise as stated the form shown in Figure 6, is the same as that shown in Figure 4.
- 10 The forms shown in Figures 4 and 6 provide for simplicity and economy in manufacture, and the benefit of quickly cutting down the size of the blind or awning body and reducing the width of the frame 15 by decreasing the length of the outer arms of the bars of the frame, and which permits quickly fitting and adjusting the same to any width window or door where the opening is less than the size of the blind as 20 originally made. This, of course, necessitates cutting off the end of the roller opposite the spring and reinserting the clip and center post.

It is also obvious that the roller can be 25 installed without the brackets 10 and 11, as notches or sockets can be cut in the frame of the door or window, one square notch permitting of the square end of the roller to be pushed inside and a round notch or socket 30 to receive the round end of the roller.

The combined awning and extension frame for the awning body 1 can be adjusted vertically, horizontally or angularly and within an arc prescribed from the roller 2 35 outside of the window or door, to the bottom thereof and inside of the door or window from the bottom to the top when the window is open in the car or door, and is so designed to be locked so as to hold the 40 awning body 1 in any desired position and by such arrangement it permits the awning body 1 to be used as a shade, visor, blind, or curtain and provides a ventilating device as well as a shade device, not only for 45 protection against sun and weather, but may be constructed of any suitable fabric or material as a sunlight visor and to prevent glare of light. When employing the awning as a sun shade or visor, the roller may be 50 placed inside or outside of the wind shield, with the holding or extension frame so constructed as to permit the shade or visor being extended and lowered any desired length and with such frame connected with 55 the wind shield in any suitable manner and locked in adjusted position.

What we claim is:

1. In rolling awnings, a fixture for the awning frame, said fixture comprising a 60 coupling member adapted to be fixedly secured in position, a bolt anchored in said member and extended therefrom, an adjustable locking member mounted on the bolt exteriorly of the coupling member and further seating in said coupling member, said

locking member formed with an opening for the passage of an arm of the awning frame, means carried by the bolt for detachably clamping said members together, and means carried by the locking member for fixedly 70 securing the arm of the awning frame thereto.

2. In rolling awnings, a fixture for an awning frame of that type having slotted side arms, said fixture comprising a coupling member adapted to be fixedly secured in position, a bolt anchored in the coupling member and extended therefrom, an adjustable locking member mounted on the bolt exteriorly of the coupling member, said 75 locking member formed with an opening for the passage of the slotted arm of the awning frame and with said opening extending at right angles to and intersected by said bolt and with the bolt positioned to extend through said slotted arm, said members having coacting means interengaging with each other when the locking member is in normal position and when adjusted, means carried by said bolt for clamping 80 said members together, and means carried by the locking member for fixedly securing the arm of the awning frame thereto.

3. In rolling awnings, a fixture for the arm of an awning frame, said fixture comprising a coupling member adapted to be fixedly secured in position, a bolt anchored therein and extended therefrom, an adjustable locking member mounted on the bolt exteriorly of said coupling member, said locking member formed with an opening for the passage of the arm of the awning frame and extending at right angles to said bolt, said members having coacting means interengaging with each other when the locking member is in normal position and when adjusted, means carried by the bolt for clamping 90 said members together, and means carried by the locking member for fixedly securing the arm of the awning frame thereto.

4. In rolling awnings, a fixture for an arm of the awning frame, said fixture comprising a coupling member adapted to be fixedly secured in position, a bolt anchored in the coupling member and extended therefrom, an adjustable locking member mounted on the bolt exteriorly of the coupling member, said locking member formed with an opening for the passage of the arm of the awning frame and extending at right angles to said bolt, means carried by the bolt and engaging with the locking member for detachably clamping said members together, and means carried by the bolt and extended at right angles to said opening for fixedly securing 100 said arm within the locking member.

5. In a rolling awning, a frame for adjusting the awning body, said frame being of yoke-shaped contour and comprising a front bar and a pair of side arms, said front 105

bar of cylindrical cross section and adapted for connection with the outer end of the awning body, said arms of rectangular cross section and each of greater width than the 5 diameter of the front bar, each of said arms formed with a lengthwise slot extending from a point in close proximity to the front

bar to a point in close proximity to the rear end of the arm.

In testimony whereof, we affix our signatures hereto.

GEORGE ENGEL.
CHARLES E. DAVIS.
